Patented Mar. 7, 1967

207,110

BREAD BOX

Harold O. Wagner, Sheffield Lake, and Manuel S. Ziskin, Mayfield Heights, Ohio, assignors to American Trading and Production Corporation, Baltimore, Md., a corporation of Maryland

Filed Apr. 29, 1966, Ser. No. 2,073

Term of patent 14 years

(Cl. D44—6)

Fig. 1

Fig. 2

Fig. 3

Fig. 4

Fig. 5

FIG. 1 is a top plan view of a bread box, embodying our new design;

FIG. 2 is a front elevational view of the bread box,

FIG. 3 is a side elevational view of the bread box, as viewed from the right side of FIG. 2;

FIG. 4 is a fragmentary cross-sectional view, taken on the line 4—4 of FIG. 2, and

FIG. 5 is a fragmentary cross-sectional view, taken on the line 5—5 of FIG. 2.

We claim:

The ornamental design for a bread box, substantially as shown.
